DESIGN FOR A JACKET

Nathan A. Rauch, New York, N. Y.

Application December 20, 1943, Serial No. 112,043

Term of patent 3½ years

To all whom it may concern:

Be it known that I, Nathan A. Rauch, a citizen of the United States, residing in New York city, in the county of New York and State of New York, have invented a new, original, and ornamental Design for a Jacket, of which the following is a specification, reference being had to the accompanying drawing, forming part thereof.

Fig. 1 is a front view of a jacket showing my design,

Fig. 2 is a rear view of the jacket shown in Fig. 1, and

Fig. 3 is an enlarged fragmentary view of the jacket shown in Fig. 1, illustrating the pocket and collar trim.

I claim:

The ornamental design for a jacket, substantially as shown.

NATHAN A. RAUCH.
